E. L. FORD.
PRESERVE JAR.
APPLICATION FILED MAR. 11, 1919.

Patented Dec. 23, 1919.

Inventor
E. L. Ford.

By *W. Randolph Jr.* *attorney.*

UNITED STATES PATENT OFFICE.

EDSON L. FORD, OF DORCHESTER, MASSACHUSETTS.

PRESERVE-JAR.

1,325,984.

Specification of Letters Patent. Patented Dec. 23, 1919.

Application filed March 11, 1919. Serial No. 281,968.

To all whom it may concern:

Be it known that I, EDSON L. FORD, a citizen of the United States, residing at Dorchester, in the county of Suffolk and 5 State of Massachusetts, have invented certain new and useful Improvements in Preserve-Jars; and I do hereby declare the following to be a full, clear, and exact description of the invention, such as will enable 10 others skilled in the art to which it appertains to make and use the same.

My invention relates to improvements in preserve jars and more particularly to the closure means therefor.

15 An important object of this invention is to provide a preserve jar wherein the closure is seated within the neck of the bottle and has its periphery spaced from the inner side of the neck of the bottle whereby an 20 annular recess is formed for the reception of sealing wax.

A further object of the invention is to provide a jar wherein the upper portion thereof is provided with an inwardly extending annular shoulder adapted for supporting a cap within the neck of the bottle, said cap being held in its position by a metallic locking element having threaded engagement with the neck of the bottle.

25 A further object of the invention is to provide a closure of the jar with an annular recess adjacent its periphery thereof for receiving a washer element adapted for coöperation with the sealing wax in rendering 30 the jar air tight.

A further object of the invention is to provide a preserve jar wherein the top thereof is easily applied and removed.

A further object of the invention is to 40 provide a jar of the character described which is simple, durable in use, and cheap to manufacture.

Other objects and advantages of the invention will be apparent during the course 45 of the following description.

In the accompanying drawings forming a part of this specification and in which like numerals are employed to designate like parts throughout the same,

50 Figure 1 is a vertical section through a jar embodied in my invention,

Fig. 2 is a plan view of the same, and,

Fig. 3 is a perspective of a device adapted for removing the top.

55 In the drawings, wherein for the purpose of illustration is shown the preferred em-

bodiment of my invention, the numeral 5 designates a jar which in this case is cylindrical. The upper portion of the jar extends inwardly as shown at 6 and is provided with an annular shoulder 7. The shoulder 7 forms a seat for a closure 8 preferably made of glass. The inner side of the closure 8 is provided adjacent its periphery with an annular recess 9 adapted for the 65 reception of a washer element 10, which may in use be of rubber or other suitable material. The periphery of the closure 8 is spaced from the curved neck 11, of the jar for forming a sealing wax receiving recess 70 12. As clearly shown in Fig. 1, the glass closure 8 does not contact with the jar, and therefore, knocking together of the several glass elements is prevented and the consequent chipping of glass eliminated. The 75 outer side of the closure 8 is provided with a concaved recess 13 in which is formed a handle 14 adapted for removing the closure 8. A locking element generally designated by the numeral 15 is provided with an annular flange 16 having threaded engagement 80 with the outer side of the flared neck 11. Inwardly extending arms 17 are carried by the flange 16 and have connection with an annular contact ring 18. As clearly shown 85 in Fig. 1, the ring 18 engages the outer side of the closure 8 at a point above the washer element 10 and securely locks the closure in position. The periphery of the closure 8 is provided with a second recess 90 19 adapted to receive a tool 20 or other suitable device for removing the top subsequent to the removal of the locking element 15. The annular recess serves also as a means 95 of anchoring the sealing wax within the recess 12.

With reference to the foregoing, it will be apparent that I have provided a jar which is extremely sanitary and desirable in use and one in which the closure may be 100 readily applied or removed.

While I have shown and described the preferred embodiment of my invention, it is understood that I may make such minor changes in arrangement and construction of 105 parts as will remain within the spirit of the invention and the scope of the appended claims.

Having thus described my invention, what I claim is:—

110 1. A jar including a body portion, a shoulder carried thereby, a neck carried by

the shoulder, a closure mounted on the shoulder and disposed within said neck, an annular flange having threaded engagement with said neck, a retaining ring engaging 5 said closure, and spaced arms connecting said ring and said flange and forming gripping members for applying and removing the retaining ring.

2. A jar comprising, a cylindrical body 10 portion, an inwardly extending annular shoulder carried by said body portion, an outwardly extending neck carried by said shoulder, a closure disposed within said neck and having its periphery spaced from 15 the inner side of said neck for forming an

annular recess adapted for the reception of a sealing element, a handle carried by said closure, and a locking element for said closure, said locking element including a threaded flange having engagement with said neck, 20 an annular ring engaging said cover and inwardly extending arms connecting said ring and said flange.

In testimony whereof I affix my signature in presence of two witnesses.

EDSON L. FORD.
